corporation of Delaware

Application January 21, 1950, Serial No. 139,839

8 Claims. (Cl. 73—74)

1

The present invention relates to a method for determining the irreducible interstitial water content, capillary pressure, and related characteristics of cores or samples of sub-surface formations.

In order to obtain a more complete analysis of core samples to determine the petroleum reserves, it is necessary and essential to determine the irreducible interstitial water content of the formation. This quantity is generally referred to as a percentage of the available pore volume of the core that is occupied by water.

The term interstitial water is defined as that water that coexists in the pore space with the oil prior to exploitation. The irreducible interstitial water content of the formation is that which is held in a state of equilibrium with the oil by capillary pressure in all of that zone of the formation which is sufficiently far above the water table to be above the transition zone. The water content of the transition zone is also a function of the capillary pressure and varies in amount with height from 100 per cent at the water table to the irreducible content at the top of this zone. The interstitial water content and the irreducible interstitial water content are numerically equal in amount in the formation where only the latter amount of water exists. The term connate water has often been used synonymously with these terms; however, this can be true only by a specific definition since, geologically, connate water is that which was entrapped in the pore spaces of the rock at the time of deposition. For the sake of brevity throughout the specification and claims, irreducible interstitial water content will be referred to as the "irreducible water."

Since the irreducible water in the formation above the transition zone is dependent on the rock structure, it is a function of the capillary pressure; and several techniques have been developed to measure this pressure and its degree of water saturation.

The methods used to determine the capillary pressure and the irreducible water may be divided into three classifications. The most prominent of these is generally referred to as the restored state method. The technique is described in detail in the literature and essentially consists of saturating a core sample with the reservoir fluid and placing it in contact with a porous membrane saturated with the same fluid. Oil, gas, or another liquid under pressure is then applied to the exposed area of the core and one side of the membrane driving the saturant from

2

the pores of the sample. The membrane is such that it will pass the saturating fluid but is impervious to the driving liquid or gas. At each applied pressure, an equilibrium saturation is obtained and the core is weighed to determine the fluid content. This pressure-saturation represents one point of a curve generally known as a capillary pressure curve. With increased pressures there is a decrease in saturation until the irreducible water is attained when there is no longer an appreciable change in the liquid content. The amount of liquid remaining in the core represents the irreducible liquid content and corresponds to a related capillary pressure.

15 This method has certain limitations since the core sample must have a flat face for complete contact with the membrane; the amount of applied pressure is limited by the capacity of the membrane. Since at every pressure there is a time required to attain an equilibrium, a period of several days is usually required to obtain the data for the capillary pressure curve and the irreducible water value.

20 The second classification includes the method of determining the capillary pressure by centrifugal force. This method of determination is essentially similar to the restored state method, except that the force driving the liquid from the pore spaces is a centrifugal force. In the determination, the speed of rotation of the sample is increased in steps until a speed is reached where any increase does not appreciably lower the water content of the core. The water driven out is measured in a pipette; and in the final determination, the loss of weight in the core is compared with the water collected in this pipette. This method is much faster than the restored state method; however, it is limited in that the speed of rotation must be constant and 25 any variation will nullify the test. In this method, the sample must have a flat face for contact with the semi-pervious membrane. Calculation of the capillary force from the rotating speed is long and involved.

30 The third method of measuring capillary pressure is based on the force necessary to drive mercury into the pore space of the core sample. This method utilizes the variation in forces necessary to change the saturation of a porous medium with mercury. The main disadvantages of this method are the core samples used are not suitable for further testing; mechanical failures and corrections for the apparatus are 35 numerous.

35 All of the foregoing procedures, as well as my

own new method to be described hereinafter, usually require that the core sample be first cleaned to remove the crude oil and related organic substances which may be present in the sample. A convenient way of cleaning, commonly used, is to extract the organic material with carbon tetrachloride in a Soxhlet extractor.

The principal object of my invention is to provide a method for determining the irreducible water with speed and accuracy.

Another object of my invention is to provide a method having calculations that are simple and direct.

Still another object is to provide a method which does not depend upon a uniformly sized and shaped sample of material and that does not alter the structure or characteristics of such sample for further testing.

Other objects and advantages will become apparent as the following description proceeds.

To the accomplishment of the foregoing and related ends, said invention then comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

Broadly stated then, this invention comprises a method for determining the irreducible water of a core sample of the sub-surface strata comprising the steps of saturating said sample with a vaporizable liquid, and while evaporating the liquid from said sample, periodically noting the decreasing weight of said sample during evaporation and subsequently determining the irreducible water of said sample from a graphical interpretation of the evaporation time-weight change relationship.

More specifically stated, this invention comprises a method for determining the irreducible water of a core sample taken from the sub-surface strata comprising the steps of saturating said core sample with a liquid evaporating the liquid from said saturated sample, determining from the inflection of the rate of evaporation curve the point at which only irreducible water remains, and calculating subsequently the actual percentage of the pore space of said sample occupied by the irreducible water.

In the further explanation of my improved method, it becomes convenient to illustrate apparatus by which such method may be carried on; two forms of such apparatus are illustrated in the drawings in which:

Fig. 1 is a diagrammatic illustration of one form of apparatus that may be used in my invention;

Fig. 2 is a diagrammatic illustration of another form of apparatus that may be used in the practice of my invention; and

Fig. 3 illustrates a typical curve showing liquid in sample versus time.

Fig. 4 illustrates capillary pressure vs. interstitial water content.

Referring now more particularly to the drawings, Fig. 1 illustrates one form of apparatus, a commercially available automatic balance, which may be used for practicing the present invention. Core sample 10 is first saturated preferably with a liquid that does not leave a residue when evaporated or cause any chemical action with the sample itself.

Examples of some of the liquids used and found

satisfactory are water, toluene, tetrachloroethane, benzene, and normal propyl alcohol. It is possible also to use liquids which have a vapor pressure greater than atmospheric at room temperatures. Examples of such liquids are a wide variety of petroleum fractions and their derivatives. Liquified propane is an example of such a liquid which will be found satisfactory for use. It will be understood, of course, that the time necessary to reach the irreducible liquid content is a function of the evaporation rate of the particular liquid used.

The reservoir fluid would, of course, be the most appropriate to use; but, since it contains salts in solution, compensation must be made for the amount of salts deposited in the pores after evaporation. This requires extra care and calculation. Distilled water, resembling most nearly the properties of the reservoir fluid, may be used on certain rock samples; however, on some structures, principally those of shaly or clay nature, it causes a swelling of the sample and a change of its characteristics.

Any of the liquids named above can be used, however, there should be a correction applied to the volume retained depending on the nature of the liquid, other than water used. This correction is a ratio of the absorption factor of the crystals to the liquid used as compared to that of water. When the core sample consists principally of CaCO_3 crystals, the correction factors for the various liquids are: 1.24 for toluene, 1.24 for benzene, 1.16 for tetrachloroethane, and 1.75 for normal propyl alcohol. If the principal core component is siliceous material then the correction factors are: 1.11 for toluene, 1.13 for benzene, and 1.11 for tetrachloroethane. A simple test to determine the principal constituents of the sample is the placing of a drop of dilute hydrochloric acid on the rock. A vigorous evolution of carbon dioxide means an abundance of CaCO_3 , while no reaction means the principal constituent is that of siliceous material. Since most core samples are made up of a combination of the two types, an average correction factor can be used for routine purposes. A value of the irreducible water as determined by using the various fluids will be shown later.

Figure 1 shows one form of balance 1 which may be used in carrying out my invention. It consists of a beam 2, a fulcrum 3, a pan 4, a weight pan 5, weights 6, and a mirror 7 onto which is projected a beam of light from a light source 8 and which beam is then reflected onto a scale 9.

The balance of the type illustrated here is in equilibrium with its full set of weights in place on platform 5 before it is put to use.

The liquid treated core sample 10 is placed in a tube 11 usually of glass, and tube 11 is placed on platform 4 of balance 1. A sufficient number of suitable weights are then removed from platform 5 which will correspond to the weight of the prepared sample and tube placed upon pan 4; the balance is thereby brought to equilibrium after which the periodic measurement of evaporation weight loss is begun. A stream of gas, ordinarily air from tube 12 is now passed over and around core sample 10 with only enough velocity to effect a rapid evaporation but not enough to agitate the balance so that a reading might be hard to obtain. Gases other than air may also be used with favorable results. Examples of these gases are nitrogen, carbon dioxide, neon, and others that do not react with the sample.

The stream of air or gas passing over the treated sample 10 causes the sample to lose weight at an approximately constant rate until a substantial part of the liquid has been evaporated from the sample. This continuous decrease in weight is noted on the scale 9. There will be a marked decrease in the rate of evaporation at a point where the forces causing the weight loss by evaporation begin to be overcome by the capillary or cohesive forces which exert the greatest effect when residual amounts of liquid remain. The water or other liquid used remaining in the core, represents the irreducible liquid present in the formation. Weight readings are taken at suitably spaced intervals of time, and these transferred to volumetric readings, are plotted on cartesian co-ordinates as a function of time which results in a curve such as is shown in Fig. 3.

The data for the curves, Figs. 3 and 4, were obtained by saturating test plug No. 8 (shown in Table I) with tetrachloroethane, water, and toluene; the points A, B, and C of Fig. 3 indicate the inflection point corresponding to the irreducible liquid content for the various fluids respectively. The points A, B, and C referred to are each the measure of the maximum amount of fluid remaining as an adsorbed film upon the internal surfaces of the sample after free evaporation of the bulk liquid from the interstitial spaces has occurred. Such remaining surface film of liquid is not free-flowing nor is it subject to free evaporation but rather to a much slower desorptive vaporization. This desorption region of the curve is substantially linear with time. Therefore, to graphically determine the point of "irreducible liquid content" requires that a sufficient number of readings be taken in the desorption region to plot a straight line. This straight line such as a—a, b—b, or c—c, in Fig. 3 is then extended to the left as shown. The tangent or inflection points A, B, and C thus formed show graphically where free liquid has disappeared and where desorption of the remaining internal surface-adsorbed liquid begins. The inflection point values are tabulated below together with the saturant absorption factors and the pore volume of the particular sample under study in Fig. 3.

Data for Limestone Sample No. 8

Core Saturant	Irreducible Liquid Content From Fig. 3, cc.	Absorption Factor of Saturant	Pore Volume of Sample, cc.	Irreducible Water, Percent Pore Volume
Tetrachloroethane	a 0.38	b 1.33	c 1.03	d 28.1
Toluene	0.40	1.40	1.03	27.8
Water	0.29	1	1.03	28.2

The "d" column expressing the desired irreducible water value is derived by applying the data for a given saturant from the first three columns according to the formula,

$$d = \frac{a \cdot 100}{b \cdot c}$$

Reasonably constant temperature conditions such as ordinarily prevail under room conditions are satisfactory for the accuracy of the method. The reason for this is that the desorptive vaporization of the adsorbed liquid film is relatively slow and little affected by temperature change in comparison with the initial evaporation of free liquid. Thus the inflection point marking the

maximum quantity of unflowable adsorbed liquid will remain substantially constant and reproducible within the normal variations of room temperature.

5 The core may be considered as being made up of two principal parts: (1) the sand grains held together by a cementing material and (2) the pore volume or free space between the grains. The pore volume may be considered as being 10 composed of capillaries capable of transmitting oil, gas, or water, and a certain volume occupied by the irreducible water retained by the smaller capillaries. This latter water, which is to be determined, will not flow from the core sample 15 even when flushed with an oil, natural gas, or other reservoir fluid.

It is to be noted that the treated core sample 18 may be placed either in a glass tube 11 as illustrated, or simply in front of a funnel through 20 which air is passed. The saturated sample 10 may be suspended in air at room temperature and pressure with no air blowing around it.

Another apparatus which may be used in the practice of my improved method is that illustrated in Fig. 2 in which the numeral 13 represents a container used as an enclosure for the apparatus. Tube 17, provided with valve 19 admits air, or other suitable gas to the container 13. The container 13 is provided with valved exhaust tubes 18 which may be connected to a vacuum pump or merely left open to the atmosphere. A pressure gauge 20 is provided to indicate the pressure within the container 13. The core sample 21 is treated in the same manner with a liquid 25 such as water or other vaporizable liquid as before described, and is held suspended from a coiled flat spring 15 by means of holder or clamp 14. The coiled flat spring 15 is rigidly attached to the top of container 13 and has a small mirror 16 fastened thereto so that any movement of the spring 15 is directly transmitted to the mirror 16. A light beam is directed on the mirror 16. As the sample changes weight, the mirror is moved by 30 consequent change in position of the spring and by passing the beam of light reflected by the mirror 16 through a window in the side of the container 13 and onto a photographic film that is moving with constant velocity at right angles to the rotation of the mirror, the evaporation rate 35 of the liquid from the sample may be recorded. Such photographic equipment has not been illustrated as it is felt that it is well known to those skilled in the art and further mention is not necessary. The determination of the irreducible water is then accomplished in the same manner 40 as before described.

At this point it may be noted that when the liquid used has a vapor pressure less than atmospheric at room temperature, the valved outlet tubes 18 may be left open to the atmosphere or connected to a vacuum pump if the evaporation rate is to be accelerated by having the pressure within the container at less than atmospheric. If the fluid used has a vapor pressure greater than 45 atmospheric at room temperature, then the valves 18 and 19 may be so adjusted that the pressure within the container is greater than atmospheric. Regardless of the specific liquid used, the control of the pressure within the container 13 may be utilized to control the evaporation rate of the liquid from the sample. By using a liquid having a vapor pressure greater than atmospheric 50 at room temperatures or by suitable pressure control over the pressure in the container the liquid 55 may be caused to evaporate at the desired rate

without the necessity of blowing a gas onto the sample.

Table I given below lists the results of tests made with various liquids and types of core samples. The agreement in the values of irreducible water shows that any of the liquids mentioned may be used in this evaporation method.

Furthermore, the evaporation method is equally applicable to core samples over a wide range of permeability to air as will be noted in Table I. Samples having very low air permeability, e. g., Nos. 7 and 8 of Table I, are subject to erratic results when tested by other methods.

up of fluid passing through the small capillaries and spreading over the surface of crystals too greatly separated to be classified as microcapillaries. The energy causing this flow has been referred to as immersional wetting and expresses the free energy change when a solid surface in equilibrium with the vapors of the liquid is covered by the liquid.

To calculate the capillary pressure, consider this energy as causing a flow of liquid to be hydrostatically balanced by an applied capillary pressure at any saturation. The following equation can be derived from the calculation of the capillary pressure and a typical curve, as ob-

As before mentioned, my method of determining irreducible water can be made on either standard plugs with flat faces, or on pieces which may be smaller with irregular surfaces which are generally known as core chips. Table II given above shows the agreement of the evaporation method, testing the same sample either as a normal test plug or as a chip of approximately 2 grams.

By my method of determining irreducible water, capillary pressures, and other related characteristics of the core sample, these properties are derived from the observed data, calculated by a hydrodynamic treatment of the data. From a standpoint of surface relationship, the test sample undergoing a saturation change by evaporation is also experiencing the flow of fluid from the inner section to the exposed surface. This flow is made

tained by this method, is shown in Figure 4, which was derived for core sample 8 shown in Table I.

60

$$P_c = \frac{as\Delta A_s}{V_1 - V_2}$$

where

65 P_c = capillary pressure

as is the energy of surface wetting

ΔA_s is the change in internal rock surface area associated with the degree of saturation

$V_1 - V_2$ is the fluid volume removed from the core sample by change in degree of saturation

70 The change in internal surface area of the rock can be calculated from the liquid flow determined from the curves represented by Figure 3. This method is, therefore, also a means of obtaining data for the calculation of the internal

75

surface area of the rock exposed to fluids available to flow.

An observed data curve such as shown in Figure 3 gives the liquid volume content as a function of time and may be represented by a decay equation of the form:

$$V = V_0 e^{-at}$$

where

V = volume of liquid in core sample at any time (t)

V_0 = volume of liquid in core sample when $t=0$, i. e., at start of evaporation test

a = an exponential constant of the equation depending on the characteristics of the core sample.

From a hydrostatic consideration it can be mathematically shown that the constant (a) of the equation is the resistance of the core sample to fluid flow and therefore an inverse function of its permeability. By applying the correct units to the constants associated with the exponent (a), the permeability can be calculated in millidarcys. My method, therefore, enables the obtaining of data sufficient for the calculations of the permeability of the core sample.

Since the core surface is exposed in all directions, the permeability found by this method is more representative of the ability of the rock structure to produce oil and/or gas than the permeability determined by methods that are unidirectional determinations.

From the foregoing description it can be seen that the present invention comprises steps of obtaining a sample, saturating it with a vaporizable liquid, and evaporating the liquid from the core sample while taking accurate weight determinations at suitably spaced intervals of time. For the purposes of this invention it has been found that an overall evaporation time of approximately one hour affords the desired results. However, it is to be noted that this time limit is not critical and may be of any duration that is practical, while still affording a rapid determination. It is also possible to determine, with the data obtained by this method, (1) the irreducible water of a porous rock sample, (2) the permeability of a porous medium, and (3) internal rock surface area and (4) the capillary pressure. This invention may be valued by the fact that the data required for calculations is obtained within one hour while these values by methods heretofore used require several days.

Other modes of applying the principle of the invention may be employed, change being made as regards the details described, provided the features stated in any of the following claims, or the equivalent of such, be employed.

I therefore particularly point out and distinctly claim as my invention:

1. A method for determining the irreducible water of a subsurface stratum comprising the steps of saturating a core sample taken from said stratum with a vaporizable liquid of known properties, evaporating the liquid from said sample, periodically weighing the sample during the evaporation, plotting a rate of evaporation curve from the findings, determining the inflection point on the curve, and determining the irreducible water of said sample therefrom.

2. A method for the determination of the irreducible water of a sample taken from the subsurface strata comprising the steps of treating the sample to remove approximately all of its

petroleum content, saturating said sample with a volatile liquid of known properties, evaporating the liquid from said sample, and determining the irreducible water of said sample from the inflection point on a plotted rate of evaporation curve.

3. A method for the determination of the irreducible water of a sample taken from the subsurface strata comprising the steps of treating

10 the sample to remove approximately all of its petroleum content, saturating said sample with tetrachloroethane, evaporating said tetrachloroethane from said sample, and determining the irreducible water of said sample from the inflection point on a plotted rate of evaporation curve.

4. A method for the determination of the irreducible water of a sample taken from the subsurface strata comprising the steps of treating

20 the sample to remove approximately all of its petroleum content, saturating said sample with toluene, evaporating said toluene from said sample, and determining the irreducible water of said sample from the inflection point on a plotted rate of evaporation curve.

5. A method for the determination of the irreducible water of a sample taken from the subsurface strata comprising the steps of treating

30 the sample to remove approximately all of its petroleum content, saturating said sample with benzene, evaporating said benzene from said sample, and determining the irreducible water of said sample from the inflection point on a plotted rate of evaporation curve.

35 6. A method for the determination of the irreducible water of a sample taken from the subsurface strata comprising the steps of treating the sample to remove approximately all of its petroleum content, saturating said sample with

40 n-propyl alcohol, evaporating said n-propyl alcohol from said sample, and determining the irreducible water of said sample from the inflection point on a plotted rate of evaporation curve.

7. A method for the determination of the irreducible water of a sample taken from the subsurface strata comprising the steps of treating

45 the sample to remove approximately all of its petroleum content, saturating said sample with water, evaporating said added water from said sample, and determining the irreducible water of said sample from the inflection point on a plotted rate of evaporation curve.

8. A method for the determination of the irreducible water and other physical properties of

55 a sample taken from the sub-surface strata comprising the steps of treating the sample to remove approximately all of its petroleum content, saturating said sample with an inert, residue free volatile liquid of known properties, evaporating the liquid by the exposure of said saturated sample to a stream of inert vapor, determining from the inflection of the rate of the plotted evaporation curve the point at which irreducible water remains, and calculating from

60 the curve other physical properties of the sub-surface strata represented by said sample thereof.
